UNITED STATES PATENT OFFICE.

BENJAMIN L. STOWE, OF NEW YORK, N. Y., ASSIGNOR OF THREE-FOURTHS
TO J. VAN D. REED, OF SAME PLACE.

KNITTED FABRIC FOR MACHINE-BELTING, &c.

SPECIFICATION forming part of Letters Patent No. 393,188, dated November 20, 1888.

Application filed December 5, 1887. Serial No. 257,025. (No specimens.)

To all whom it may concern:

Be it known that I, BENJAMIN L. STOWE, of the city, county, and State of New York, have invented a certain new and useful Improvement 5 in Knitted Fabrics for Machine-Belting and other Purposes, of which the following is a specification.

The invention is an improvement upon the machine-belted knitted fabric shown and described in Letters Patent No. 321,153, of June 30, 1885. The said patented knitted fabric is a solid knit selvaged fabric of the width required for the belt, having incorporated in it straight longitudinal strands and a weft, and 15 also binding-strands, if desired.

The improvement I have made on this fabric consists in adding to the fabric a second strand of weft and in so placing or depositing the two weft-strands that they shall be on opposite 20 sides of the longitudinal strands, which latter consequently extend and are held between said weft-strands. This change in or addition to the fabric effects a substantial improvement. It neutralizes and removes a tendency to roll 25 laterally, which the fabric as before made possessed, while the face of the fabric is rendered smoother and more uniform. The improved fabric, when used for machine-belted, will better hold a lacing or other device for 30 connecting its two ends, and it is less liable to be imperfectly knitted in consequence of the additional weft serving to hold the knitting warp or strand in such a position during the process of knitting that when a stitch has been 35 dropped by a needle, at the succeeding operation of the needle the stitch will again be caught and perfect knitting resumed, whereas as the fabric has heretofore been made the knitting warp or strand would not be again 40 caught by the needle until assisted by the operator.

Machinery for producing this fabric is not here described or claimed, the same being reserved by me for a separate application for 45 Letters Patent.

The fabric which is the subject of my present application is illustrated in its preferred form in the accompanying drawings.

Figure 1 is a very much enlarged representation in plan of a portion of a solid knit selvaged fabric embodying my improvement. In the

actual web or fabric the strands are of course packed closely together. They are represented in the drawings enlarged and widely separated in order that the structure of the fabric may 55 be more readily understood. Fig. 2 is a similar view of a modification.

The fabric shown in Figs. 1 and 2, with the exception of the second or additional weft-strand, is precisely like that described in my 60 aforesaid Letters Patent, No. 321,153, with reference to Figs. 5 and 6 of the drawings annexed to said Letters Patent, A being the knitting warps or strands, which are worked into a series of zigzag looped stitches alternately to one side, and the other of warp-strands B, which are worked into a series of rows of straight looped stitches. D are the longitudinal strands laid along the rows of loops formed by the warps B. E is the weft or 70 filling, and C are the binding-warps.

This fabric, which is one having all the looped stitches upon one and the same face of the fabric, is substantially the same as that which is shown and described in my aforesaid 75 Letters Patent. The addition which I have made to said fabric is the weft or filling E', which is laid upon the side of the longitudinal strands opposite that upon which the weft E is laid, and which is held in the fabric by the 80 same stitches which hold the weft E.

Machinery for making this improved fabric has been made by me the subject of a separate application for Letters Patent, filed November 30, 1887, Serial No. 256,560, to which reference 85 may be had for a full understanding of the same and its mode of operation. Fig. 2 differs from Fig. 1 only in the different specific arrangement of the two wefts. They retain, however, their general position therein with 90 relation to the longitudinal strands the same as in Fig. 1.

Having described my improvement, what I claim, and desire to secure by Letters Patent, is as follows:

1. A solid knit selvaged fabric, all the looped stitches of which are on one and the same face of the fabric and are composed of alternate rows of straight stitches B and zigzag stitches A, having incorporated in it straight longitudinal strands, and also two wefts or sets of wefts, E E', deposited upon opposite sides of 95 100

the longitudinal strands and secured in the fabric by the same stitches, substantially as hereinbefore set forth.

2. A solid knitselvaged fabric, all the looped 5 stitches of which are on one and the same face of the fabric and are composed of alternate rows of straight stitches B and zigzag stitches A, having incorporated in it straight longitudinal strands and binding strands, and also 10 two wefts or sets of wefts, E E', deposited

upon opposite sides of the longitudinal strands and secured in the fabric by the same stitches, substantially as hereinbefore set forth.

In testimony whereof I have hereunto set my hand this 3d day of December, 1887.

BENJAMIN L. STOWE.
